[57] CLAIM

The ornamental design for a dental post, as shown and described.

DESCRIPTION

FIG. 1 is a perspective view of a dental post showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof;

FIG. 7 is a perspective view of a second embodiment thereof;

FIG. 8 is a top plan view thereof;

FIG. 9 is a front elevational view thereof;

FIG. 10 is a bottom plan view thereof;

FIG. 11 is a perspective view of a third embodiment thereof;

FIG. 12 is a front elevational view thereof, all sides being identical, the top plan view being identical to FIG. 8;

FIG. 13 is a perspective view of a fourth embodiment thereof;

FIG. 14 is a top plan view thereof;

FIG. 15 is a front elevational view thereof; and

FIG. 16 is a bottom plan view thereof.
